UNITED STATES PATENT OFFICE.

CHARLES MAYER, OF NEW YORK, N. Y.

IMPROVEMENT IN BOOTS AND SHOES.

Specification forming part of Letters Patent No. **43,784**, dated August 9, 1864; antedated June 3, 1864.

To all whom it may concern:

Be it known that I, CHARLES MAYER, of the city, county, and State of New York, have invented a new and useful Improvement in Boots and Shoes; and I do hereby declare that the following is a full, clear, and exact description of the same, reference being had to the accompanying drawings, making part of this specification, in which—

Figure 1 represents a sectional side elevation of my invention. Fig. 2 is a rear elevation of the same.

Similar letters of reference in both cases indicate corresponding parts.

This invention relates, particularly, to an improvement in laced shoes or "balmoral" boots, and the principal object of the invention is to enable the wearer to take off said boots or shoes without unlacing them simply by withdrawing a pin. Furthermore, by the application of my invention to boots or shoes the ankle of the foot is braced or supported, and the wrinkling or creasing of those parts contiguous to the back seam of such boots or shoes is prevented.

The nature of the invention and its peculiarities will be readily understood from the following description.

A represents a shoe, made of leather or any other suitable material, and of that class generally known by the term of "balmoral boots." My invention, however, is not confined to this particular class of boots or shoes, and I have only represented a shoe of this kind because it is best adapted to give an illustration of the nature of my improvement. The back seam of this shoe, instead of being produced by stitching, is composed of a series of loops or hinges, *a*, which are secured to the leather or other material composing the shoe by means of rivets *b*, or in any other suitable manner. A pin, *c*, passing through the hinges *a*, closes the back seam perfectly firm. The hinges *a* extend down to the cap *d*, the upper part of

which is made of india-rubber cloth or other elastic material, and the pin *c* is made of copper wire or other soft material, so that the same allows the hinges *a* to accommodate themselves to the sinuosities of the foot, as clearly shown in Fig. 1 of the drawings.

The shoe is fastened in front by lacing *e* in the usual manner, and in putting it on the pin *c* is inserted into the hinges *a*, and the lacing is unfastened the same as it is in putting on a shoe of the ordinary construction. The operation of taking off the shoe, however, is considerably facilitated, and it can be accomplished simply by withdrawing the pin *c* without unfastening the lacing. After the shoe has been taken off the lacing can be unfastened at leisure and perfectly easy, while the operation of unfastening the lacing before the shoe is taken off is tedious and annoying, particularly in dirty weather, where such boots are particularly worn.

By the application of the hinges *a* to the back seam of a boot or shoe still another advantage is obtained. Said hinges support the ankle and prevent the wrinkling and creasing of those parts contiguous to the back seam. A boot or shoe constructed according to my invention, therefore, retains its shape until it is completely worn out and the heel is not liable to wear uneven.

I do not claim, broadly, the invention of a back opening, for my improvement is not limited by the position of the opening; but

What I claim as new, and desire to secure by Letters Patent, is—

The employment of the pin *c* and hinges *d* in combination with boots and shoes, substantially in the manner and for the purpose herein shown and described.

CHAS. MAYER.
